(57) **CLAIM**

The ornamental design for a connecting element for sheet piles, as shown and described.

DESCRIPTION

FIG. 1 is a perspective view of a connecting element for sheet piles; and,

FIG. 2 is a side view thereof.

All portions of the connecting element for sheet piles located between the break lines, shown throughout the drawing disclosure, form no part of the claimed design.

1 Claim, 2 Drawing SheetsFIG. 1

FIG. 2
